UNITED STATES PATENT OFFICE.

WILLIAM THOMAS MILLER, OF FRESNO, CALIFORNIA.

SAFETY-RAZOR-BLADE SHARPENER.

1,292,844.

Specification of Letters Patent. Patented Jan. 28, 1919.

Application filed April 8, 1918. Serial No. 90,010.

To all whom it may concern:

Be it known that I, WILLIAM THOMAS MILLER, a citizen of the United States, residing at Fresno, in the county of Fresno and State of California, have invented certain new Improvements in Safety-Razor-Blade Sharpeners, of which the following is a specification.

This invention relates to a simple and efficient apparatus for sharpening safety razor blades and has for its object to provide in such a machine an article of few parts readily portable and of an economical construction and novel design by means of which safety razor blades may be quickly and easily sharpened to a desired keenness for shaving.

With this end in view the apparatus consists of the novel combination and arrangement of parts hereinafter described and pointed out in the appended claims, reference being had to the accompanying drawings, in which:

Figure 1 is a front elevation of the apparatus mounted on a support and ready for use.

Fig. 2 is a vertical central sectional view of the same, and,

Fig. 3 is a plan of the sharpening disk. Referring to the drawing by numerals, 10 indicates the sharpening disk made in the present instance of two sheets of leather 11 and 12 of circular form and of different diameters and qualities. The lower larger sheet or disk 11, made of a size most suitable and convenient, is preferably a leather having a coarse and somewhat rough surface upon which is mounted a second sheet 12 made of leather with a fine grain and concentrically disposed upon the disk 11, its edge 13 being beveled as shown and spaced from the outer edge 14 of the disk 11 to provide a surface 15 for first acting on the razor blades to give them a rough sharpening, after which the blades are brought to a keen cutting edge upon the upper surface 16 of the disk 12.

The sharpening disk 10 may be rotated

at high speed by any suitable means, the disk having a hole through its center whereby it is mounted axially upon a revolving shaft or spindle and secured rigidly thereon. One means by which the disk may be conveniently used is illustrated in the drawing and as there shown an upright frame 17 is 50 screwed or bolted to a support such as a bench or table 18 and in a bearing 19 formed with said frame 17 is a shaft 20 fixed in said bearing and projecting horizontally from the front thereof. Upon the shaft is mounted to rotate a beveled gear wheel 21 which may be turned by a handle 22 thereon, said gear wheel meshing with a small beveled pinion 23 on the lower end of a vertical shaft 24 turning in a bearing 25 on the top 55 of the frame 17. The upper end of the shaft 24 is threaded and screwed thereon is a metal plate 26 sufficiently large to properly support and uphold the polishing disk 10 which is placed upon said plate, the end of the 60 shaft 24 passing through the central hole therein and secured in place by a nut 27 and washer 28 that presses down upon the top or section 12 of the sharpening disk.

In use, the razor blade is secured in a suitable holder and held first upon the surface 15 of the coarse leather disk 11 with one hand while the other hand rotates the gear wheel 21 and the sharpening disk. The blade holder being held at a proper angle 75 the blade will be roughly sharpened and when this disk 11 has brought the blade to a suitable condition the same is transferred to the disk 12 of fine leather where it is given its final whetting and polishing and 80 brought to the desired keenness for shaving.

I claim:

1. A tool sharpening machine comprising an upright rotatable shaft, a disk clamped at its center on said shaft and formed of two superposed concentric sheets of leather of different qualities and diameters, said disk being unsupported at its edge to permit of flexion of the working portion under pressure of the tool being sharpened.
2. A tool sharpening machine comprising

an upright rotatable shaft, a disk mounted at its center on said shaft and formed of a lower sheet of flexible self-sustaining leather unsupported at its edge and a smaller sheet 5 of finer leather mounted concentrically upon the lower sheet, and a metal plate on the shaft below the disk and of smaller diameter than either leather sheet, whereby the

edges of the latter are permitted to flex under pressure.

In testimony whereof I have affixed my signature in the presence of two witnesses.

WILLIAM THOMAS MILLER.
